CHARLES H. SHEPARD, OF BRIDGEPORT, CONNECTICUT.

BOLT FOR MACHINE-GUNS.

1,284,478.

Specification of Letters Patent. Patented Nov. 12, 1918.

Application filed April 10, 1918. Serial No. 227,614.

To all whom it may concern:

Be it known that I, CHARLES H. SHEPARD, a citizen of the United States, and resident of Bridgeport, in the county of 5 Fairfield and State of Connecticut, have invented certain new and useful Improvements in Bolts for Machine-Guns, of which the following is a specification.

The object of the invention is to cheapen 10 the manufacture and improve the construction of bolts such as are used in the type of machine-gun recently adopted by the United States Army and known as the Browning gun. In these guns a reciprocating bolt carries a firing-pin longitudinally movable within it, and this firing-pin has an offset, 15 tapered firing-point, which in the act of firing projects through an offset, tapered firing-hole in the bolt at the forward end of 20 the chamber in which the firing-pin works. The production of the offset, tapered hole in the bolt has been a matter of substantial difficulty and expense, owing to a preliminary operation which has heretofore been 25 necessary, this operation being delicate and costly in its nature and of no benefit in the completed weapon, but merely for the purpose of affording room for the passage of the reaming tool which brings the initial 30 parallel-sided hole to the desired taper. The operation in question is the formation of a side cut in the firing-pin chamber of the bolt, inclining from a point intermediate the ends of the chamber to a sufficient depth at 35 the forward end to permit the reamer to act.

By my invention I do away with this troublesome step, by means of an altogether 40 different operation, which is of exceedingly simple character and correspondingly insignificant expense, and the result of which is of permanent value in the gun. This step 45 consists in making a transverse bore or drilling in such manner as to intersect the rear portion of the firing-hole, or the region corresponding thereto, producing an enlargement of sufficient size and suitable form to receive the broad basal portion of the firing-point. This cross-bore eliminates the necessity of reaming out the back of the hole, 50 and all that remains is a slight reaming-out of the small forward part thereof, which can readily be accomplished without cutting into the side of the firing-pin chamber of the bolt.

In the accompanying drawings: 55

Figure 1 is a longitudinal section through the bolt and firing-pin illustrating the invention;

Fig. 2 is a cross-section on the line 2—2 of Fig. 1; 60

Fig. 3 is a perspective view of the forward end of the firing-pin;

Fig. 4 is a fragmentary longitudinal section through the bolt as previously made; 65

Fig. 5 is an enlarged fragmentary cross-section through this construction.

The drawings represent the bolt 2 of a Browning gun. The relation of this bolt to parts of the weapon other than the firing-pin 3 has not been illustrated because unnecessary to an understanding of the invention. As those familiar with this type of machine-gun are aware, the bolt is guided for longitudinal reciprocation, and in the 70 operation of the gun vibrates back and forth. It contains a longitudinal chamber 4, fitted slidably by the firing-pin.

The firing-pin 3 is a hollow cylinder or 75 rod, containing the spring chamber 5. In this chamber is a helical compression spring 6, introduced through the open front end of the firing-pin and confined between a cross-pin 7 in the forward part of the firing-pin and a vertical pin 8 secured in the bolt 80 and passing through a slotted opening in the firing-pin. When the firing-pin is forced rearward in the bolt the spring has its compression increased and tends to drive the firing-pin forward. At the rear of the firing-pin is a catch shoulder 9 to engage a 85 sear 10, which is actuated by a spring 11. The firing-pin is forced rearward in the bolt into engagement with the sear by a lever 12 pivoted at 13 in the bolt and adapted to 90 engage at its upper arm with a relatively stationary part (not shown) as the bolt travels rearward. Release of the sear by means not shown permits the firing-pin to 95 shoot forward. 100

14 is the offset firing-point, consisting of a forward projection from the bottom part of the wall of the firing-pin. This firing-point is large at the base, its greatest dimension being horizontal, and tapers to a small striking extremity. The outer and inner surfaces of the firing-point are convex and concave, respectively, being continuations of 105

the outer and inner curvatures of the pin. The firing-point operates through a firing-hole 15 extending through the front wall of the bolt and correspondingly offset at the bottom of the firing-pin chamber 4. It is in the novel form of this hole and its method of production that the invention resides, the other features described being old.

Heretofore it has been customary to make the firing-hole by drilling a larger hole part way through from the inside and a smaller hole from the outside to meet it, and then reaming out this two-diameter hole from the inside to the tapered form shown at 15^a in Fig. 4. This reamed-out hole was circular in all its cross-sections, and since its rear part had to be wide enough to take in the greatest width of the base of the firing-point 14, it followed that its bottom arc had to cut below the bottom of the firing-pin chamber 4. This necessitated, as a preliminary operation, the making of the sloping cut *a* in the bottom side of the chamber, which side cut is difficult and expensive as heretofore stated. In my invention the rear part of the firing-hole which receives the broad base of the firing-point is formed or is enlarged, as the case may be, by a portion of a small cross-bore 16, which is drilled in from one side of the bolt 2, terminating therein somewhat past the chamber 4. This cross-bore intersects the rear of the firing-hole or the axis thereof and also cuts into the front end of the chamber 4, and forms in effect a wide and sufficiently high entrance affording adequate clearance for the base of the firing-point.

The forward part 15^b of the hole, which it will be understood already exists as a small drill-hole, is now reamed out to an appropriate taper, but this operation does not require any side cut such as shown at *a* in Fig. 4.

The advantages of my construction and procedure are fully set forth in the introductory part of the specification.

What I claim as new is:

1. In a firearm comprising a firing-pin having an offset tapered point and a bolt chambered to receive the firing-pin and having an offset firing-hole, a bolt characterized by a transverse bore intersecting the inner part of the firing-hole which receives the broad basal portion of the point.

2. In a firearm comprising a firing-pin having an offset tapered point and a bolt chambered to receive the firing-pin and having an offset firing-hole, a bolt characterized by a transverse bore intersecting the inner part of the firing-hole which receives the broad basal portion of the point, the portion of the firing-hole in front of said transverse bore being reamed out.

3. In a machine-gun having a firing-pin with an offset tapered point, a part wherein said firing-pin operates having a longitudinal chamber for the pin and an offset firing-hole and characterized by a transverse bore forming an enlarged junction between the inner portion of the firing-hole and the chamber, for the purpose set forth.

4. A part to constitute the bolt of a machine-gun, said part having a longitudinal chamber and an offset firing-hole to receive a firing-pin having an offset tapered point, characterized by a transverse bore intersecting the inner part of the firing-hole and of a size to afford clearance for the basal portion of the point and to permit the part of the hole in front of said transverse bore to be reamed out without cutting into the side of the chamber.

In testimony whereof, I have signed my name to this specification.

CHARLES H. SHEPARD.
